UNITED STATES PATENT OFFICE

EDWARD E. JOHNSON, OF ST. PAUL, MINNESOTA

MEANS FOR MAINTAINING A SUBSTANTIALLY CONSTANT LEVEL OF LIQUIDS IN TANKS

Application filed May 15, 1925. Serial No. 30,514.

My invention relates to means for maintaining a substantially constant level of liquid in tanks. This invention is in the nature of an improvement on the device disclosed and claimed in Letters Patent of the United States No. 1,463,986 granted August 7, 1923, to Herbert L. Wherland. While obviously adapted for other uses, it relates more particularly to devices for use in connection with water towers of water supply systems. An object is to provide a compact self-contained instrument comprising the necessary height of mercury column. Another object is to provide an efficient electrical device which will operate to start the flow of liquid from a source of supply into the tank when the liquid therein falls to what is considered the permissible minimum level and which will operate to stop the flow of liquid into the tank when the desirable maximum level in the tank is reached. Another object is to provide a device of this character which can be readily adjusted or set so that the tank may be kept substantially full or may be kept at any other desired depth of liquid and which can be adjusted so that the fluctuations between maximum and minimum depths may be varied.

The full objects and advantages of my invention will appear in connection with the detailed description thereof and the novel features embodied in my inventive idea will be particularly pointed out in the claims.

In the accompanying drawings which illustrate a practical embodiment of my invention in one form, Fig. 1 is an elevational view showing my invention applied to a water tower. Fig. 2 is a view in cross-section on the line 2—2 of Fig. 3. Fig. 3 is a vertical sectional view of the device. Fig. 4 is a view in horizontal section on the line 4—4 of Fig. 3. Fig. 4A is a view on an enlarged scale of a portion of Fig. 4. Fig. 5 is a view in horizontal section on the line 5—5 of Fig. 3. Figs. 6, 7 and 8 are wiring diagrams showing certain parts moved successively into different positions.

In the embodiment of the invention chosen for illustrative purposes and referring first to Fig. 1 a pump 10 draws water through

a pipe 12 from the source of supply and delivers it to a pipe 14 which is connected to the usual distribution system by pipe 15 and through a riser pipe 16 with a tank 18 mounted on supports 20 to constitute a water tower. The pipe 14 is also connected with a vertical pipe 22 provided with a needle valve 24 best shown in Fig. 3 and the purpose of which will be explained later. The pipe 22 is connected with a horizontal pipe 26 which in turn is joined by an elbow connection to a T 28 from which a pipe 30 leads to a pressure gauge 32. The principle of operation underlying the mechanism of Wherland in U. S. Pat. No. 1,463,986 already referred to and that involved in this application is identical: viz. the balancing of a head of water by an equivalent head of mercury. A water head of 135 feet for example is balanced by a head of approximately 10 feet of mercury. Such heads of water and greater are commonly used and the corresponding lengths of mercury column—as in Wherland—are unwieldy and difficult to set up. To overcome this obstacle and produce a compact instrument, easy to install, I provide a plurality of U-tubes 35, 43 and 49 Fig. 3 of such number and such length (commonly about four feet) as will together have the aggregate capacity required in the head of mercury. These tubes are preferably of steel and are filled to about one half their height with mercury M to a common level such as indicated by the line M—M' in Fig. 3, altho great accuracy in this respect is not necessary. The initial end 34 of the first U-tube 35 extends somewhat above the common mercury level M' occupied when the instrument is under atmospheric pressure, and is connected to the water supply thru the pipe 22 as shown. The U-tube 35 terminates by branch 36 in a head-block 38 which should be made of bakelite or other suitable insulating material the necessity for which will be explained later, and to which it is secured in a liquid-tight manner as by screw threading for example. The next U-tube 43 in the series terminates in the embodiment shown with both branches 42 and 44 in the headblock 38. Other and similar U-tubes not shown in this embodiment may

be similarly included in the series should it be necessary in order to increase the capacity of the instrument. The final U-tube 49 as shown terminates in the headblock 38 by its initial branch 48 and by its final branch 50 in the contactor 51 which will be described later on. The headblock 38 is provided with chambers 41 and 45 connecting the adjacent branches of U-tubes 35 and 43 and 48 and 49 respectively. Chambers 41 and 45 are open through the top of the block 38 for convenience in filling the instrument and are provided with liquid-tight caps 40 and 46. If U-tubes 35, 43 and 49 are now filled with mercury to their half-height M' , it is evident that the pressure resisting capacity of each is measured by the maximum difference in level obtained when the mercury is forced downward to M_2 in the initial branch 48 and upward to M_3 in the final branch. In order to avail myself of the total capacity of the series of U-tubes, I fill them above the mercury, with an insulating liquid O of light specific gravity preferably a mineral oil thru and including the chambers 41 and 45. It will be understood that the oil is very much lighter than the mercury and always remains at the top and the mercury cannot pass from one U-tube to another. The mercury columns for each U-tube therefore will always have their predetermined heights for any given pressure in the liquid system. The final branch 50 of U-tube 49 is joined by a union 52 to the lower end of a tube 54 of bakelite or other insulating material, the upper end of this tube being secured for convenience in an opening in the headblock 38. A metal tube 56 which constitutes part of the contactor 51 is slidably mounted in the tube 54, the upper end of the tube 56 extending above the tube 54 and being secured in a socket in an insulating block 58. The tube 56 is encircled by a metal pinch band 60 shown in Fig. 4 and carried by a bracket 62 secured to the headblock 38. The tube 56 is provided with a longitudinal slot 57 as shown in Fig. 4A to prevent the formation of an air pocket due to change in the mercury level. A wire 64 is secured to the bracket 62. A metal rod 66 is encased in a fixed covering 67 of insulating material and this composite rod is mounted in the metal tube 56, so that it may be slid therein when released as will be explained later. The metal rod 66 at its extreme lower tip is preferably convex and is bare of insulating material while the upper portion of this rod is also bare and extends through an opening in the block 58 and through an opening in a metal sleeve 68 mounted in the block. The branch 50 contains only mercury which under pressure extends up into the tube 54 so that at the proper time it may make contact with the lower end of the metal tube 56 as well as with the metal rod 66.

The liquid tight caps 40 and 46 are secured in place and the U-tubes constitute, for operative purposes, one continuous tube, so that pressure applied to the initial branch of the U-tube 35 is resisted in part by the unbalanced mercury therein and in part by the unbalanced mercury in the U-tubes 43 and 49 to which the pressure is transmitted by the intervening pistons of oil O, and the total load impressed on the U-tube 35 is thus distributed among and borne by all the tubes of the series. I am thus able to provide the necessary mercurial balance for the widely varying pressures encountered in practice by varying the height and number of the U-tubes and still keep the instrument in a compact form which is convenient and practical to erect and operate. A screw 70 threaded into the sleeve 68 engages the rod 66 and holds it adjustably in place in the block. A wire 72 is attached to the sleeve 68, and as will be seen from Figs. 6, 7, and 8 this wire includes the coil of an electro-magnet 74, the outer end of the wire being connected to a contact post 76. The wire 72 is connected by a branch wire 78 with a contact post 80 which will be referred to later. The wire 64 includes the coil of an electro-magnet 82, the outer end of this wire being connected to a contact post 84. The wire 64 is connected by a branch wire 86 with the armature 88 of the electro-magnet 82 and is also connected by a branch wire 90 with the armature 92 of the electro-magnet 74. The metal U-tube 49 has a wire 94 connected therewith, this wire in Fig. 3 being shown connected with the branch 48 near its upper end altho it may be attached at any convenient position along this tube. The final U-tube 49 is made a part of the electrical circuits of the instrument and the U-tubes 35 and 43 are not; it is necessary therefore to insulate it from them. To do this, I make the headblock 38 of bakelite or other insulating material and as the oil O is a non-conductor of electricity, the insulation of the circuit including the U-tube 49 is provided for at this point. The pinch band 60 is for the same reason spaced away from the metal cap 46, and the branches 48 and 50 are held in place by insulating blocks thus completely insulating the final U-tube 49 from the rest of the instrument. The wire 94 joins with a wire 94' which includes the coil of an electro-magnet 96, the outer end of this latter wire being connected to a contact post 98. The wire 94' is connected by a branch wire 100 with a switch arm 102 adapted to be moved into engagement with either the contact post 76 or a contact post 104 by means of an insulative link 106 which connects the arm 102 with the armature 92. This armature when retracted engages a contact post 108 which is connected by a branch wire 110 with the wire 72. The electro-mag-

net 96 has an armature 112 which when attracted thereby engages a contact post 114 connected by a branch wire 116 with the wire 100. When the armature 112 is attracted, the outer end 118 thereof engages the post 84. This outer end is insulated from the main portion of the armature at 120 and this outer end is connected by a metal link 122 with the outer end 124 of a switch arm 126 from the main portion of which this end is insulated at 128. When the armature 112 is attracted, the arm 126 engages the contact post 80 and the insulated end 124 engages a contact post 130 which is connected by a branch wire 132 with the wire 72. The armature 112 is connected by a wire 134 with one pole of a motor 136, the other pole of which is connected by a wire 138 with the arm 126. This motor drives the pump 10. The wire 20 leading to the post 76 also leads through a green lamp 140 while a branch wire 142 connected to the post 104 leads through a red lamp 144. The supply wire from any suitable source of electricity is connected to a post 146 which is joined by a fuse 148 with a post 150 to which the wires 94 and 94' are secured. The wire 72 is connected to a post 152 which is joined by a fuse 154 to a post 156 to which the return wire to the electrical source is connected. If it were not for the insulation 67 which allows only the extreme lower end of the rod 66 to come into engagement with the mercury, the contact between this rod and the mercury would not be readily broken since the mercury would tend to stick to the side of the rod when the level of the mercury is below the end of the rod. The provision of a restricted passageway in the pipe section 22 such as produced by the proper setting of the needle valve 24 prevents variations of pressure in the water system from causing a surging movement being transmitted to the mercury and oil in the U-tubes. These tubes may be secured to the wall of a room or to some other vertical support in any suitable manner. As shown, three similar angle strips 158, 160 and 162 are secured to the support in vertical spaced relation. The headblock 38 is secured to the strip 158 as shown in Fig. 4. The middle and lower portions of the U-tubes are secured to the strips 160 and 162 respectively, as shown in Fig. 5 by being clamped between pairs of insulating blocks 164 and 166. The strips 158, 160 and 162 are held together by two vertical angle bars 168 welded thereto whereby the tubes are held together as a unit for convenient handling and installation. By referring to Fig. 1, it will be understood that the electro-magnets 74 and 82 and the associated contacts are placed in a box 170 and that the electro-magnet 96 and the associated contacts are placed in a box 172. These boxes are secured in suitable manner to the support and are connected by a tube 174 through which the proper wires pass, and the wires connected to the motor pass through a tube 176 extending from the box 172.

The operation and advantages of my invention will be apparent in connection with the foregoing description. When the level of the water in the tank falls so that there is not sufficient pressure to maintain the mercury in contact with the lower end of the rod 66, the electro-magnet 74 is de-energized and its armature 92 comes into contact with the post 108 while the connected switch arm 102 comes into contact with the post 104 as shown in Fig. 6. This causes current to flow from the supply wire in the path indicated by the single feathered arrows in this figure. From the post 150, the current flows through the wire 94' including the coil of the electro-magnet 96, to the post 98, through the armature 88, wire 86, a portion of the wire 64, the wire 90, the armature 92, to the post 108, through the wire 110 and to the return wire connected to the post 152. Current also flows as indicated by the double feathered arrows from the post 150 through the wire 100, arm 102, post 104, red lamp 144 and wire 72 to the return wire. The energization of the electro-magnet 96 attracts its armature 112 and brings it into contact with the post 114 while the arm 126 is brought into contact with the post 80. Current now flows as indicated by the triple feathered arrows from the wire 100 through the wire 116, to the post 114, through the armature 112, through the wire 134, the motor 136, the wire 138, the arm 126, to the post 80, through the wire 78 and wire 72 to the return wire. This energizes the motor and causes it to operate the pump. When the increased pressure of water in the tank is sufficient to cause the mercury to rise slightly and engage the lower end of the rod 66, a circuit is completed through this rod as will be apparent from Fig. 7 and current now flows as indicated by the single feathered arrows from the post 150 through the wire 94 to the mercury in the tube 49, through the rod 66, the wire 72, including the coil of the electromagnet 74 and to the return post 152. The energization of the electro-magnet 74 attracts the armature 92 and draws it from engagement with the post 108 and pulls the arm 102 into contact with the post 76. Current now flows as indicated by the double feathered arrows from the post 150 through the wire 100, arm 102, green lamp 140, and wire 72 to the return post. The current continues to flow as indicated by the triple feathered arrows through the wire 116 to the post 114, through the armature 112, the wire 134, the motor, the wire 138, the arm 126, and the wire 78 to the wire 72 and return post 152. Current through the electro-magnet 96 now flows as follows as indicated by the quadruple feathered arrows, through the wire 94' 130

including the electro-magnet 96 to the post 98, through the armature 88, the wire 86, the wire 64, to the post 84, through the link 122 to the post 130, through the wire 132 to the wire 72 and the return post 152. When the mercury rises to the bottom of the tube 56 as shown in Fig. 8, a circuit is completed through this tube and current at first flows as indicated by the single feathered arrows 5 through the wire 64 including the coil of the electro-magnet 82 to the post 84, through the link 122, to the post 130 and through the wire 72 to the return post. Energization of the electro-magnet 82 attracts its armature 88 and breaks connection with the post 98 so that the circuit through the electro-magnet 96 is broken, and the armature 112 retracts thereby moving it from contact with the post 114 and causing the arm 126 to move from contact with the post 80 so that the circuit through the motor is broken and the pump stops. It will be understood that this action takes place almost instantaneously. Current continues to flow as indicated by the double feathered arrows in this figure through the wire 100, the arm 102, the green lamp 140 and wire 72 to the return post. Current also flows as indicated by the triple feathered arrows from the rod 66 through the wire 72 including the coil of the electro-magnet 74 and to the return post 152. This maintains the armature 92 in the engagement with the electro-magnet 74 until the level of the water in the tank falls sufficiently to permit the mercury to drop below the lower end of the rod 66 whereupon the cycle of operations previously described is repeated. It will be understood from Fig. 6 that as soon as the mercury lowers sufficiently to break contact with the lower end of the rod 66, the red light comes on but goes off almost immediately when the pump starts and causes the increased pressure of water to again bring the mercury into contact with the rod 66. If for any reason the pump fails to work and raise the level in the tank, the red light will stay on and indicate that something is wrong. At other times, the green light is on which indicates that the system is functioning properly. By referring to Fig. 3, it will be understood that when the pinch band 60 is loosened, the rod 66 together with the metal tube 56 may be raised and lowered which will result in varying the level at which the water in the tank is maintained. Also by loosening the screw 70, the rod 66 may be raised and lowered relatively to the tube 56 whereby the range between maximum and minimum depths of water in the tank may be varied.

60 I claim:

1. In a device of the class described, the combination of a tube containing mercury subjected to the pressure of a liquid, a contact rod extending into said tube and covered with a fixed layer of insulating material with

the extreme lower end of the rod left bare, a tubular contact member extending into said tube around said insulating layer, connections with one of said contact members which cause the current to flow when the pressure of the liquid falls to a predetermined amount, and connections with the other of said contact members which cause current to be cut off when the pressure of the liquid rises to a predetermined amount. 70

2. In a device of the class described, the combination of a tube containing mercury subjected to the pressure of a liquid, said tube having a lower metallic portion and an upper portion of insulating material, a contact rod extending into said insulating portion and stopping short of said metallic portion, said contact rod being covered with a layer of insulating material with the extreme lower end of the rod left bare, a tubular contact member filling the space between said insulating layer and said insulating portion of the tube and of less length than said rod, connections with said rod which cause current to flow when the pressure of the liquid falls to a predetermined amount, and connections with said tubular member which cause current to be cut off when the pressure of the liquid rises to a pre-determined amount. 80 95

3. In a device for maintaining a substantially constant level of liquids, the combination of a system of substantially parallel vertical tubular members containing mercury and connected with each other at the bottom and having the intermediate members connected with each other at the top, a connection with one of the outside members whereby the mercury is subjected to the pressure of the liquid whose level is to be maintained constant, and two electrical contacts in the other of the outside members through which an electrical circuit is completed by the rise of mercury in said last mentioned member. 100 105

4. In a device for maintaining a substantially constant level of liquids, the combination of a system of substantially parallel vertical tubular members containing mercury and connected with each other at the top, a connection with one of the outside members whereby the mercury is subjected to the pressure of the liquid whose level is to be maintained constant, means for restricting the passage through said connection to prevent surging of said liquid, and two electrical contacts in the other of the outside members through which an electrical circuit is completed by the rise of mercury in said last mentioned member. 110 115 120

5. In a device for maintaining a substantially constant level of liquids, the combination of a plurality of U-tubes containing mercury and connected with each other in series at their upper ends, a connection with one of the outside branches of said tubes whereby the mercury is subjected to the pres- 125 130

sure of the liquid whose level is to be maintained constant, and two electrical contacts in the other of the outside branches of said tubes through which an electrical circuit is completed by the rise of mercury in said last mentioned branch.

In testimony whereof I hereunto affix my signature.

EDWARD E. JOHNSON.
